UNITED STATES PATENT OFFICE

165,741

PLATE OR THE LIKE

Philip R. Costigan, Hamburg, Pa., assignor to Castleton China Incorporated, New York, N. Y., a corporation of New York

Application July 17, 1951, Serial No. 15,921

Term of patent 14 years

(Cl. D44—15)

To all whom it may concern:

Be it known that I, Philip R. Costigan, a citizen of the United States of America, residing at Highland Acres, Hamburg, county of Berks, State of Pennsylvania, have invented a new, original, and ornamental Design for a Plate or the like, of which the following is a specification, reference being had to the accompanying drawing, forming part thereof.

In the drawing:

Fig. 1 is a top plan view of a plate, showing my new design, and

Fig. 2 is a side elevation thereof.

I claim:

The ornamental design for a plate or the like, as shown.

PHILIP R. COSTIGAN.
